Inventor:

William B. Sullivan.

By

Fred J. Larson,
Attorney.

UNITED STATES PATENT OFFICE.

WILLIAM B. SULLIVAN, OF ST. LOUIS, MISSOURI.

REMOVABLE SAW-HANDLE.

1,301,522.

Specification of Letters Patent. Patented Apr. 22, 1919.

Application filed April 29, 1918. Serial No. 231,510.

To all whom it may concern:

Be it known that I, WILLIAM B. SULLIVAN, a citizen of the United States, residing in the city of St. Louis and State of Missouri, have 5 invented certain new and useful Improvements in Removable Saw-Handles, of which the following is a specification.

My invention relates to improvements in removable saw-handles and practical fastening means therefor, for conveniently and securely positioning and locking the handle to the end of a saw-blade and yet permit ready and quick removal of the handle from the saw-blade when it is desired to place the 10 same in a tool-box, thereby substantially shortening the saw-proper and enable it to be packed in a tool-box shorter in length than would be required for the saw were the handle not removable.

20 A further object of the invention is to provide a removable saw handle and fastening means therefor which is a distinct and practical improvement in saw art to overcome certain important practical objections to, 25 and defects in the usual means of affixing handles to saw blades.

I attain these and similar objects by the construction, arrangement and combination of parts more fully described in the following specification and finally pointed out in the claim hereto appended.

Referring to the accompanying drawings forming a part of this specification wherein like characters of reference denote similar 35 parts throughout the several views:

Figure 1, is a side elevation of a saw-blade, removable-handle and fastening means therefor constructed in accordance with my invention, the handle being shown 40 detached in full lines and partially removed in dotted lines.

Fig. 2, is a side elevation of a saw-blade showing the fastening receiving slots formed in one end thereof.

45 Fig. 3, is a detail taken on line X—X of Fig. 1.

Fig. 4, is a longitudinal sectional view of the fastening means carried by the handle.

50 Fig. 5, is a detail, in section, of one of the female fastening members.

Fig. 6, is a detail in side elevation of the male fastening member.

Fig. 7, is a bottom plan view of the saw-handle, blade and the spring locking means.

55 Referring to the drawings the reference character 1 designates an ordinary standard

saw-blade while 2 designates the usual saw-blade handle having the hand gripping portion 3.

The saw-blade 1 is provided at one end 60 with a slotted opening 4 having an upper open end communicating with the upper edge of the saw-blade near the upper corner 5 thereof. The saw-blade 1 is further provided with the slotted opening 6 having an 65 outer open end communicating with the beveled edge 7. The slotted opening 6 is positioned below and to one side of the slotted opening 4. The saw-blade 1 is still further provided with a third slotted opening 8 having 70 an outer open end communicating with the beveled edge 7. The slotted opening 6 is provided with the curved upper edge 9 which is the arc of a circle using point 10 of slot 4, as a center. The slotted opening 8 is provided with the curved upper edge 11 which is the arc of a circle using point 10 of slot 4, as a center.

75 The saw blade 1 is still further provided with a downwardly and inwardly extending 80 slotted opening 12 having its outer end communicating with the beveled edge 7 of the saw-blade. The upper edge of the slotted opening is suitably curved, as at 13, the reason being apparent hereinafter. The inner 85 end of the slotted opening 12 terminates in an upwardly extending slot 14 thereby providing a locking-lip 15 at the lower end of the curved edge 13, as clearly shown in Fig. 2. The slotted opening 12, it will be ob- 90 served is in turn positioned below the slotted opening 8.

The saw-blade handle 2 is provided with the usual blade receiving slot 16, as shown in Figs. 3 and 4.

95 The saw-blade handle 2 is further provided with three interlocking fasteners, as shown in Fig. 1, one for each slotted opening 4, 6 and 8.

The female member of the fasteners consists of a hollow-stem member 17 having an open end provided with the interior screw-threads 18. The hollow stem is further provided with the flanged head 19 having a screw-driver receiving slot 20 formed in its 100 outer face.

The male member of the fasteners consists of a shank portion 21 having a diameter equal to the diameter of the hollow-stem member 17. The shank portion 21 is provided with the exteriorly screw-threaded stem 22 upon one end thereof and with a 110

flanged head 23 on the opposite end. The head 23 is provided with a screw-driver receiving slot 24 formed in its outer face.

When the two fastener members are interlocked, it will be observed that the connection between the two heads 19 and 23 is united by a connector of uniform diameter throughout its length.

Preferably three fasteners are adapted to 10 be carried by the wood-handle 2 in the transverse openings 25, 26 and 27 thereof. First the hollow-stem members 17 are inserted into their respective openings in the handle 2, spanning the slotted saw-blade receiving 15 slot 16 and extending clear through the handle. After these hollow-stem members have been positioned the stem 22 is screwed into position in the hollow-stem member, as clearly shown in Figs. 3 and 4.

20 It will be observed that the interlocking fasteners are each so positioned that the top fastener carried in opening 25 is, in placing a handle upon a blade, first inserted into the slotted opening 4, to act as a pivot or hinge. After this operation the handle, is forced home, as shown in full lines from the position shown in dotted lines in Fig. 1, causing the remaining two fasteners to enter their respective slots 6 and 8. When the 25 handle is being finally forced home or into its normal position it will be observed that the end 28 of a spring-keeper or locking catch 29 strikes the curved edge 13 and finally the lip 15 passes through the slotted 30 opening 30 of the keeper and is engaged by the cross-piece 31 which holds and locks the saw-handle firmly in its assembled position, as shown in full lines in Fig. 1. To remove the handle all the operator does is 35 to release the spring keeper from engagement with the lip 15 of the saw-blade 1 and pull out and up on the saw handle or in other words, gives the handle an upward turning movement using the upper interlocking fastener as a pivot or hinge. After 40 the two lower fasteners have been removed from the receiving slots 6 and 8, respectively, the handle can be lifted off so as to remove the upper fastener from its receiving slot 4.

50 It will thus be seen that the saw-handle can be easily and quickly affixed to the saw-blade 1 or removed therefrom and placed

in a tool box of considerable shorter length than would be required were the handle 55 positively fixed to the saw-blade 1.

It will be here understood that the interlocking fasteners herein described act as positioning stops when received by the slotted openings in the saw-blade. 60

The many advantages of the herein described invention due to the construction shown and described and the method of attaching and locking or removing the saw-handle from the saw-blade will be readily 65 apparent to those skilled in the art to which the invention appertains.

While I have described the principle of operation or adjustment of the invention, together with the structure of devices I now 70 consider to be the best embodiment thereof, I desire to have it clearly understood that the device shown is merely illustrative and that I reserve the right to make any such 75 changes or modifications as may fairly fall within the principle of the invention and within the scope of the appended claim when fairly construed.

What I claim is:

A removable handle for saw-blades, in 80 combination, a handle having a saw-blade receiving slot, a plurality of suitably spaced interlocking fasteners carried thereby and adapted to span the saw-blade receiving slot thereof; a saw-blade having a plurality of 85 fastener receiving slots formed at one end thereof and so arranged that when the upper fastener of the handle is inserted into its receiving slot in the saw-blade it acts as a hinge upon which the handle may swing 90 in a downward turning movement for inserting the remaining lower fasteners into their respective slotted openings in the saw-blade, a lock lip formed at one end of the saw-blade below the lowermost fastener receiving slot, a spring locking catch fixed to the lower face of the handle provided with a slotted opening adapted to receive the lock lip and a portion of said spring catch adapted to engage behind said lock lip for holding the handle in a normally locked position upon one end of the saw-blade. 95

In testimony whereof, I have hereunto signed my name to the specification.

WILLIAM B. SULLIVAN.
